UNITED STATES PATENT OFFICE.

CHARLES E. GASKILL, OF EL PASO, TEXAS.

PISTOL-HOLSTER.

1,120,190.

Specification of Letters Patent.

Patented Dec. 8, 1914.

Application filed February 4, 1914. Serial No. 816,443.

To all whom it may concern:

Be it known that I, CHARLES E. GASKILL, a citizen of the United States, residing at El Paso, in the county of El Paso and State of Texas, have invented new and useful Improvements in Pistol-Holsters, of which the following is a specification.

This invention relates to a pocket holster for a pistol or revolver and is intended primarily as an improvement over my prior patent, which bears the Serial Number 896,004, and is dated August 11, 1908. This improved form of holster has resilient pocket-engaging members which are disposed normally in engaging position and are adapted to become engaged automatically with the sides of the pocket when the holster is inserted within the same without the necessity of operating the said members in any special manner. A readily operable releasing device is provided for use as a handle in withdrawing the holster from the pocket and which is adapted to render the pocket-engaging members inoperative during this act of withdrawal. This releasing device is adapted however, to permit the pocket-engaging members to resume their normal positions due to their own resiliency as soon as the device is released from the grasp.

A further object of the invention is to provide a holster of this character which includes a flat back adapted to fit snugly within the pocket of the wearer's clothing, and a gun-receiving pocket arranged upon the outer face of the back which is disposed at such an angle that the grip of the gun will be maintained in a position wherein it may be grasped conveniently and the firearm may be withdrawn quickly and with a minimum amount of exertion. The holster is therefore adapted particularly for use in a hip-pocket, for the reason that it is necessary to draw the firearm laterally as well as upwardly in extracting the same from the holster.

Another object is to construct the back of the device with the upper portions of its side edges substantially parallel whereas the lower portions thereof, coextensive with the pocket-engaging members are cut so as to converge downwardly to a slight extent. When the pocket-engaging members are moved inwardly against the side edges of the back, by their engagement with the edges of the wearer's pocket, during the act of insertion, they will still be inclined at a

slight angle to the longitudinal axis of the back, whereby the said act will be greatly facilitated. When the pocket-engaging members are drawn inwardly by the use of the means provided for the purpose in the act of withdrawal, the downward convergence of the said members in their inoperative positions will likewise permit the holster to be withdrawn freely and without pulling out the lining of the pocket in which the holster is mounted.

The invention consists in the features of construction, combination, and arrangement of parts, hereinafter fully described and claimed, reference being had to the accompanying drawings, in which:

Figure 1 is a front elevation of the pocket holster, showing the pocket-engaging members in their operative positions; Fig. 2 is a rear elevation, the position of the releasing member as operated to release the pocket-engaging members being shown in dotted lines; and, Fig. 3 is a horizontal sectional view taken through the device as shown in Fig. 1.

In the drawing, the numeral 1 designates the back of the holster which is preferably flat and consists of rear and front sheets of leather 2 and 3 which are marginally stitched together. A pocket 4 for the reception of a pistol or revolver is stitched to the front sheet 3 and is inclined laterally so as to facilitate the extraction of the firearm therefrom. Pocket-engaging members 5 are disposed at the side edges of the back and are formed by the side portions of a substantially U-shaped resilient wire 6, whose cross portion 7 is arranged along the lower edge of the back and is secured medially thereto by means of the tubiform member 8. The members 5 are normally inclined away from the side edges of the back toward their upper ends, which latter are bent inwardly as at 9 to form locking shoulders for engagement with the sides of a pocket in which the holster may be placed. The end portions 9 of the pocket-engaging members project into slots 10, formed in the side edges of the back by interrupting the stitching at points adjacent to the upper edge of the back, and are movable therein. These ends of the said members are provided terminally with loops or eyes 11 and 11^a to which the ends of a flexible releasing member 12 are connected. This releasing member is preferably in the form of a string

or a strip of leather, and is movable through the laterally spaced eyelets 13 and 13^a which are provided in the rearmost sheet 2 of the back. The end portion of the releasing member 12 which extends inwardly through the eyelet 13 is connected with the end loop 11^a of one pocket-engaging member, whereas the opposite end portion extends inwardly through the eyelet 13^a, crosses the other end portion and is connected with the end loop 11 of the opposite pocket-engaging member. The eyelets project outwardly from the sheet 2 so as to space the medial portion of the releasing string from the back in order that it may be grasped readily with the fingers when it is desired to pull the same upwardly and thus draw the free ends of the pocket-engaging members inwardly into their inoperative positions, and these outwardly projecting portions of the eyelets are reinforced by surrounding rings 14, which may be constructed of leather. When the said members are in their operative positions, the releasing member 12 will be taut. When the pocket-engaging members are in their innermost inoperative positions, they will be disposed in contact with the side edges of the pocket, the coextensive portions of the side edges being cut so as to converge downwardly, in order that the pocket-engaging members will be inclined with respect to the longitudinal axis of the back even when inoperative, so that the holster may be inserted into and withdrawn from the wearer's pocket easily and freely without disarranging the pocket lining. In placing the holster in the pocket, it is merely necessary to force the same downwardly without the necessity of manipulating the releasing member, owing to the inclination of the pocket-engaging members, the latter being forced inwardly into inoperative position by their engagement with the upper edge of the pocket during this operation. When the holster has been inserted into the pocket completely, the pocket-engaging members will have assumed their operative positions wherein they will secure the holster positively against outward movement. In removing the holster from the pocket, the medial portion of the releasing string must be grasped and pulled outwardly as a handle whereupon the pocket-engaging members will first be released and the holster will be withdrawn by the one operation.

What is claimed is:

1. A pocket holster comprising a back, a pistol pocket thereon, a substantially U-shaped spring carried by the back and having its side portions bent into pocket-engaging members, each member being inclined outwardly from the back toward its free end and having its free end bent inwardly to form a locking shoulder, and means by

which said pocket-engaging members may be drawn inwardly into inoperative position.

2. A pocket holster comprising a back, a pistol pocket thereon, a substantially U-shaped spring carried by the back and having its side portions bent into pocket-engaging members, each member being inclined outwardly from the back toward its free end and having its free end bent inwardly to form a locking shoulder, and a flexible releasing member connecting the free ends of the pocket-engaging members. 75

3. A pocket holster comprising a back having alining slots in its side edges, a substantially U-shaped spring having its cross portion secured to the under edge of the back, the side portions of the said spring being inclined outwardly toward the upper end of the back to form yieldable pocket-engaging members and having their free ends bent inwardly to form locking shoulders, the free ends of the said members being movable within the back slots, the back being provided with laterally spaced openings inwardly of the said slots, and a flexible releasing member mounted within the said openings with its ends connected to the free ends of the pocket-engaging members and with its medial portion disposed exteriorly of the pocket. 80 85

4. A pocket holster comprising a back having alining slots in its side edges, a substantially U-shaped spring having its cross portion secured to the under edge of the back, the side portions of the said spring being inclined outwardly toward the upper end of the back to form yieldable pocket-engaging members and having their free ends bent inwardly to form locking shoulders, the free ends of the said members being movable within the back slots, a pair of laterally spaced eyelets provided in the back inwardly of the said slots so as to project outwardly therefrom, and a flexible releasing member extending through the said eyelets with its medial portion disposed outward from the back in spaced relation thereto and with its ends connected to the free ends of the pocket-engaging members, the said releasing member being adapted to be taut when the engaging members are in their operative positions. 100 105 110

5. A pocket holster comprising a back having alining slots in its side edges, a substantially U-shaped spring having its cross portion secured to the under edge of the back, the side portions of the said spring being inclined outwardly toward the upper end of the back to form yieldable pocket-engaging members and having their free ends bent inwardly to form locking shoulders, the free ends of the said members being movable within the back slots, the back being provided with laterally spaced open- 115 120 125 130

- ings inwardly of the said slots, and a flexible releasing member mounted within the said openings with its ends connected to the free ends of the pocket-engaging members and 5 with its medial portion disposed exteriorly of the pocket, the releasing member having each of its ends extending laterally from the opening in which it is movably mounted and connected with the oppositely disposed 10 pocket-engaging member.
6. A pocket holster comprising a back, a pistol pocket thereon, a substantially U-shaped spring carried by the back and having its side portions bent into pocket-engag- 15 ing members, each member being inclined outwardly from the back toward its free end and having its free end bent inwardly to form a locking shoulder, and means by which said pocket-engaging members may be drawn inwardly into inoperative posi- 20 tion, those lower portions of the side edges of the back coextensive with the pocket-engaging members being formed to converge downwardly.

In testimony whereof I affix my signature 25
in presence of two witnesses.
